(57) **CLAIM**

The ornamental design for a bottle closure, as shown and described.

DESCRIPTION

FIG. 1 is a perspective view of a bottle closure showing our new design;

FIG. 2 is a front view of the bottle closure depicted in FIG. 1;

FIG. 3 is a side view of the bottle closure depicted in FIG. 1 representing a partial rotation of the bottle closure about its vertical center axis from the perspective view depicted in FIG. 1;

FIG. 4 is a top view of the bottle closure depicted in FIG. 1; and,

FIG. 5 is a bottom view of the bottle closure depicted in FIG. 1. The broken lines shown in FIG. 5 are for illustrative purposes only and form no part of the claimed design.
